THOMAS W. BRANCH, OF COLUMBUS, GEORGIA.

GAME APPARATUS.

1,273,024.

Specification of Letters Patent. Patented July 16, 1918.

Application filed December 5, 1916. Serial No. 135,215.

To all whom it may concern:

Be it known that I, THOMAS W. BRANCH, a citizen of the United States, residing at Columbus, in the county of Muscogee and 5 State of Georgia, have invented new and useful Improvements in Game Apparatus, of which the following is a specification.

This invention is an improved game apparatus, especially cards for playing a game 10 which I call the game of "Uncle Sam", and comprising a pack of fifty-two cards, one for each State and Territory and each inscribed with a point number, with geographical data, and also with a suit symbol, 15 as hereinafter described.

The invention consists in the features of construction, combination, and arrangement of devices, hereinafter fully described and claimed.

20 In the accompanying drawings:—

Figures 1, 2, 3, 4, and 5, are plans of cards each of a different suit and inscribed and arranged in accordance with my invention.

My improved game apparatus is a pack of 25 fifty-two cards. Fifty of the cards are arranged in suits of ten each. Each suit card is inscribed with a suitable suit symbol, which may be a red mark 1, a white mark 2, a blue mark 3, stars 4, or stripes 5, as shown on the drawings. Each card also has 30 a point number 6 in diagonally opposite corners, the point numbers ranging from 1 to 52 consecutively. Each card is also inscribed as at 7 with the name of a State, 35 Territory, or district and is also inscribed directly under its point number, as at 6^a, with the abbreviation of the name of said State, Territory, or district. The abbreviation and at least one figure of the point 40 number corresponds in color with the suit symbol.

Each card is also inscribed at 8 with a sectional designation, as Southern or the like, and is inscribed as at 9 with the population of said State or other political division. Each card is also provided as at 10 with the name of the capital of the State or other political division, together with the population of the capital, and is also inscribed as at 12 with the name of the largest city in the State or other political division, and the population of said largest city. Each card is also inscribed as at 13 with the names of the States or water bodies, or 55 foreign nations, constituting the boundaries of the State or other political division indicated by the card.

Hence the cards are educational and teach the players the population of the States or other political divisions, the relative sizes 60 thereof, the capitals and larger towns thereof, the position and boundaries thereof. The point numbers indicate the relative sizes of the States. When playing the game, 10, 20, 30, 40, and 50 each count ten points, 5, 65 10, 15, 25, 35, and 45, each count five points, 11, 22, 33, and 34, count 1, 2, 3, and 4 points respectively the State or other political division in which the game is being played, counts five points, the capital of the United 70 States counts five points and the person holding the greatest number of cards is also entitled to claim five points, making a total of one-hundred points in the game. The taking of tricks is covered as follows: 75 When the cards have been distributed, when say four persons are playing, the person to the right of the dealer plays his card on the board, the others following suit by playing cards representing the State bounding the 80 lead card if possible and otherwise playing any other card. The card bearing the highest number or in other words the largest State played, provided it is the one led, or a State bordering on the one led takes the 85 trick and the person taking such card leads again and so on until all the cards have been played. The number of points made by each player are noted and count toward 90 winning the game which may be set at one-hundred, two-hundred, or three-hundred, as decided by the players. When a game is played in which trumps are named, the two extra cards numbered 51 and 52 are discarded.

Having described the invention, what is claimed is:

The herein described game card inscribed with the name of a political division, a word indicating the section in which said political division is located, and also with a number indicating the relative rank of said political division and also indicating the point value of said card, said number being distinctive in appearance and said card also having a 100 suit symbol which corresponds with the distinctively indicated point number.

In testimony whereof I affix my signature.

THOMAS W. BRANCH.
